CLAIM

The ornamental design for a pump for liquids, as shown and described.

DESCRIPTION

FIG. 1: Axonometric view of first embodiment of the pump for liquids;

FIG. 2: Front view thereof;

FIG. 3: Left view thereof;

FIG. 4: Back view thereof;

FIG. 5: Right view thereof;

FIG. 6: Bottom view thereof;

FIG. 7: Top view thereof;

FIG. 8: Axonometric view of second embodiment of the pump for liquids;

FIG. 9: Front view thereof;

FIG. 10: Left view thereof;

FIG. 11: Back view thereof;

FIG. 12: Right view thereof;

FIG. 13: Bottom view thereof; and,

FIG. 14: Top view thereof.

The portions of the pump for liquids shown in broken lines in the figures form no part of the claimed design.

1 Claim, 14 Drawing Sheets
